UNITED STATES PATENT OFFICE.

WILHELM A. ZIETZKE AND HENRY C. SUMMERS, OF BOZEMAN, MONTANA TERRITORY.

CHURN.

SPECIFICATION forming part of Letters Patent No. 364,744, dated June 14, 1887.

Application filed January 22, 1887. Serial No. 225,161. (No model.)

To all whom it may concern:

Be it known that we, WILHELM A. ZIETZKE and HENRY C. SUMMERS, citizens of the United States, residing at Bozeman, in the county of Gallatin and Territory of Montana, have invented a new and useful Improvement in Churns, of which the following is a specification.

Our invention relates to an improvement in churns; and it consists in the peculiar construction and combination of devices, that will be more fully set forth hereinafter, and particularly pointed out in the claims.

In the drawings, Figure 1 is a side elevation of a churn embodying our improvement. Fig. 2 is a vertical longitudinal sectional view of the churn-body. Fig. 3 is a vertical transverse sectional view of the same. Fig. 4 is a detail perspective view of one of the beaters.

A represents a vertical supporting-frame having the sides or standards B, which are connected together by means of transverse stays or braces C. From the inner sides of the vertical frame, at the corners thereof, project headed studs or pins D.

E represents a rectangular churn-body, which may be made of wood, sheet metal, or any other preferred material, and is provided with a water-chamber, F, which extends entirely around its sides and ends. The sides of the churn-body are provided with sheets or panes of glass, G, so that light may be admitted to the interior of the churn-body when the top or cover thereof is on. This cover H is provided with a depending flange, I, adapted to fit between the sides and end of the churn-body, and that portion of the projecting flange or edge of the cover which extends beyond the depending flange and bears upon the upper edges of the churn-body is provided with a packing, K, made of cork, leather, rubber, or other suitable material, the object of the said packing being to effect a water-tight joint between the cover and the churn-body. The

cover is also provided with circular glass panes L, which enable the operator to see the contents of the churn-body, and thus ascertain at a glance whether the butter is formed or not while the operation of churning is in progress. From the bottom of the churn-body, at the ends thereof, extend faucets M, the func-

tion of which is to draw the buttermilk from the churn-body when the churning operation is completed, so as to leave the butter in the churn-body, where it may be readily worked and salted.

On the under side of the churn-body, near the ends thereof, are arranged transverse bars N, in the ends of which are secured projecting threaded studs O. The width of the churn-body is such that it may be placed between the sides or standards of the supporting-frame, and the churn-body is suspended in the frame by means of links P, the upper ends of which are pivoted upon the studs D, and the lower ends of which are pivoted upon the studs O. By means of these links the churn-body is adapted to reciprocate lengthwise to and fro between the sides of the frame, and also to alternately rise and fall simultaneously with its longitudinal movement, thus effecting a maximum agitation of the cream within the churn-body, and causing the same to be violently dashed first against one end of the churn-body, and then against the other end thereof.

In the center of the cover is an opening, O', which forms a vent. The cover is secured in position on the upper side of the churn-body by means of a series of clamps, S, which are secured on the sides and ends of the churn-body. Each clamp comprises a base-piece, T, secured to the churn-body on the outer side thereof, and having the ears t, a curved arm, t', the lower end of which is pivoted between the ears, and a thumb-screw, t'', which engages a threaded opening in the free end of the arm. After the cover is placed on the churn-body, the clamping-arms are turned upwardly to the position shown in the drawings, and the thumb-screws are turned so as to bear downwardly upon the cover, and thus secure the latter firmly on the churn-body.

U represents a pair of beaters, which are placed in the churn-body, each beater comprising an inclined board, V, having depending supporting-feet V' at its ends, which bear squarely against the bottom of the churn-body, and at its upper side is provided with a vertical yoke, V'', which is made of wire, and is adapted to bear against the cover of the churn-body, so as to retain the beater therein in the position indicated in Fig. 2. It will be ob-

served by reference to the said figure that the beaters are arranged in the churn-body with their inclined sides approaching each other, and that the spaces formed under the lower 5 sides of the beaters by reason of the depending supporting-feet constitute channels to admit the free passage of the currents of cream lengthwise in the churn-body.

In order to prevent the beaters being forced out of place by the action of the cream in churning, the top bar of the yoke V^2 may be fitted in a groove formed on the under side of the lid or held between two pins or stops thereon.

From one side of the churn body, at the center thereof, projects a headed stud, W . X represents a rod, which has its upper end slotted and pivoted upon the said stud, the lower end of the said rod being pivoted to one 25 side of the supporting-frame at the bottom thereof.

Y represents a hand-lever, which has its lower end pivoted on the opposite side from the rod X , the said hand-lever Y being provided, at a suitable distance from its lower 25 end, with a longitudinal slot, Z . A pin or bolt, A' , projects from the outer side of the rod X and works in the slot.

In order to operate the churn-body, the hand-lever Y is grasped and moved back and forth lengthwise against one side of the frame, thus imparting an oscillating vibratory motion to the churn-body, and consequently causing the contents thereof to be violently agi-

tated and churned into butter in a comparatively short time. The water-space surrounding the sides and ends of the churn-body permits hot or cold water to be placed therein, so as to raise or lower the temperature of the cream in the churn to the requisite degree for 35 securing the best results in churning.

Having thus described our invention, we claim—

1. The combination of the frame or stand, the depending links pivotally connected thereto, and the churn-body suspended by the said links, and thereby adapted to oscillate, the rod X , pivoted to the stand or frame and connected to the churn-body, and the hand-lever Y , pivoted to the stand or frame and 45 connected to the rod X , the said rod X having a projecting bolt or pin working in a slot made in the lever Y , substantially as described.

2. The beaters arranged at a suitable angle, having the depending feet adapted to bear 55 against the bottom of the churn-body, and provided with the upwardly-extending yoke-frame detachably secured to the top of the churn-body, so as to secure the beaters in place, substantially as described.

In testimony that we claim the foregoing as our own we have hereto affixed our signatures in presence of two witnesses.

WILHELM A. ZIETZKE.

HENRY C. SUMMERS.
